[57] CLAIM

The ornamental design for an eyewear front, as shown and described.

DESCRIPTION

FIG. 1 is a front, elevational view of an eyewear front showing our new design;

FIG. 2 is a right side view thereof, the side opposite being a mirror image;

FIG. 3 is a top, plan view thereof;

FIG. 4 is a bottom, plan view thereof;

FIG. 5 is a front, perspective view thereof; and,

FIG. 6 is a rear, perspective view thereof.

The broken line showing of the eyewear temples in FIGS. 1-6 is for illustrative purposes only and forms no part of the claimed design.
